UNITED STATES PATENT OFFICE.

LINDSAY H. CRAWFORD, OF CHICAGO, ILLINOIS.

UNDERWEAR.

1,140,121.

Specification of Letters Patent. Patented May 18, 1915.

Application filed December 26, 1913. Serial No. 808,683.

To all whom it may concern:

Be it known that I, LINDSAY H. CRAWFORD, a citizen of the United States, residing at Chicago, in the county of Cook and State 5 of Illinois, have invented certain new and useful Improvements in Underwear, of which the following is a specification.

This invention relates to union suits of underwear for men, women and children.

10 The object of the invention is to afford increased protection to the back, chest and abdomen. This object I attain by providing the body of the garment with a lining of suitable fabric, as will appear hereinafter.

15 In the accompanying drawings Figure 1 is a front view of a union suit embodying the features of my invention, a part of the leg portions of the garment being omitted. Fig. 2 is a sectional view taken in the plane of 20 dotted line 2—2 of Fig. 1. Fig. 3 is a section on dotted line 3—3 of Fig. 1.

The body 1 and leg portions 2 may be knit in one piece as usual, or made in any other suitable way, and the arm portions 3 may 25 be knit of the same material and sewed to the body, in the customary manner. The body is provided with a lining 4 of any suitable fabric, preferably a fabric that is softer and more agreeable to the touch than 30 the fabric composing the body, arms, and legs. The lining 4 is coextensive with the front, back and sides and extends downwardly to a horizontal plane adjacent to the crotch. The body 1 has the usual opening 35 down the front thereof. The lining is secured in place by the seams or lines of stitching formed at the junction of the arms and the body, around the edges of the reinforcing piece 5 along the lines of buttons 40 and button holes provided at the edges of the opening in the front of the body, and adjacent to the fly 6 at opposite sides of the posterior utility opening longitudinally of said opening, which opening extends upwardly from a point adjacent the crotch 45 region. It will thus be seen that except at its edges the inner fabric is substantially free from the outer fabric; hence there is a certain amount of air in the interstices between the two fabrics, which improves the heat insulating qualities of the garment, and

tends to prevent the outer fabric from becoming wet with perspiration.

In use, the garment affords warmth where warmth is most needed, namely, about the 55 chest, abdomen and back. The single thickness of fabric in the arm and leg portions not only affords sufficient protection, owing to the activity and movement of the limbs, but is desirable in that excessive warmth is 60 avoided.

In a garment made of ribbed fabric, there are spaces or grooves between the ribs. These spaces in the body fabric are substantially filled by the ribs on the lining fabric, 65 whereby the heat retaining quality of the garment is materially improved. The use of two fabrics promotes durability. Moreover the suit retains its original shape and fit. 70

I claim as my invention:

1. A union suit of underwear having an opening down the front of the body, the arm and leg portions being of single thickness and the body being of double thickness, 75 the inner thickness consisting of a separate piece of fabric sewed to the outer thickness along the upper edge of the garment at the junction of the arms and the body, and also at the edges of said opening, the lower portion of the inner thickness extending down to a point adjacent to the crotch, whereby 80 to protect the abdomen and the lower portion of the back of the wearer.

2. An article of underwear having a body 85 of ribbed fabric and a lining of ribbed fabric, said lining being substantially co-extensive with the front, back and sides of the body and terminating at its lower end adjacent to the crotch of the garment so as to 90 protect the abdomen and the lower portion of the back of the wearer, the ribs of the two fabrics intermeshing, whereby the spaces between the ribs on one fabric will be filled or closed by the ribs on the other 95 fabric.

3. A union garment of underwear comprising, in combination, a body portion and leg portions connected thereto, said garment having a posterior opening extending upwardly from a point adjacent the crotch region, and a lining comprising portions ly- 100

ing on the inside of the body portion and secured thereto longitudinally of the garment at opposite sides of said opening.

4. A union garment of underwear comprising, in combination, a body portion of elastic fabric and leg portions connected thereto, said garment having a posterior opening extending upwardly from a point adjacent the crotch region, and a lining of

elastic fabric comprising portions lying on 10 the inside of the body portion and secured at opposite sides of said opening.

In testimony whereof I affix my signature in presence of two witnesses.

LINDSAY H. CRAWFORD.
